HYDRAULIC TAPPET

Oscar H. Bunker, Evanston, Ill., assignor to New Products Corporation, Chicago, Ill., a corporation of Delaware

Application March 9, 1949, Serial No. 80,569

20 Claims.

(Cl. 123—90)

1

The present invention relates to an improved hydraulic tappet of the type widely employed in automotive engine installations.

Hydraulic tappets now on the market have certain recognized limitations which it has long been sought to overcome. In an attempt to hold oil leak-by in the tappet to a minimum, extreme accuracy and closeness of tolerance in the manufacturing operations are required, incidentally adding materially to the cost of production. If the engine oil which is usually employed as the tappet pressure liquid is not changed at sufficiently frequent intervals, it becomes heavy and gummy with the result that the check valves and closely fitted, lapped surfaces characteristic of the tappet construction often become clogged and cease to function properly.

Furthermore, the diameter of the parts which are subject to hydraulic pressure is kept as small as possible, with the result that extremely high hydraulic pressures arise, again multiplying the tendency toward leak-by.

It is also a fact that tappets change in their operating characteristics in accordance with the temperature of the engine and tappet, and resultant change in size due to expansion or contraction of the tappet parts. This change must be compensated for in a perfect tappet. Moreover, inasmuch as most existing hydraulic tappets are designed to take up all cam-tappet backlash in an automatic fashion, a new, modified cam shaft is required in order to maintain its original efficiency of operation. Frequently a tappet is not operable at full efficiency until several cam cycles have been performed and proper operating pressure built up therein.

To my knowledge no one has yet succeeded in devising a hydraulic tappet which meets all of the tappet requirements under the above described conditions of oil deterioration, variable operating temperature, control of leak-by and perfect timing with backlash control, yet which can be manufactured reasonably economically.

It is therefore an object of the invention to provide an improved hydraulic tappet which operates with unimpaired efficiency under all conditions which it is likely to meet in the normal life of an automotive motor installation, and which is not subject to loss of inefficiency due to changes in its pressure liquid.

A further and more specific object is to provide a hydraulic tappet which insures minimum oil leak-by in operation, due to the fact that the pressure in the compression chamber of said tappet acts on a surface of relatively large area.

2

thereby reducing unit pressure on the parts, yet which does not require a high degree of accuracy in the manufacture and interfitting of its parts.

Yet another object is to provide a tappet which automatically compensates for variations in dimension of its parts under the effects of temperature changes, thereby maintaining proper valve timing throughout the life of the installation.

10 A still further object is to provide a tappet of the foregoing type which is instantaneously operable at full efficiency when operation of the motor is started, due to its provisions for constantly maintaining a supply of pressure liquid available at the tappet pressure surfaces.

The foregoing statements are indicative in a general way of the nature of the invention, but other and more specific objects will be apparent to those skilled in the art upon a full understanding of the construction and operation of the device.

A single embodiment of the invention is presented herein for purpose of illustration, but it will be appreciated that the invention may also be incorporated in other modified forms coming equally within the scope of the appended claims.

In the drawing, the figure is a view on enlarged scale in vertical, axial section through a tappet in accordance with the present invention, showing said tappet in its operative relation to an actuating cam and to a valve stem controlled by the tappet.

The reference numeral 10 generally designates the hollow cylindrical body of the tappet, adapted to be slidably mounted in a bore in the engine block. Body 10 is closed at its lower end by a pressure plate 11 adapted to ride on the conventional cam 12 (shown in minimum lift position). Approximately medially of its axial length, the body 10 is provided with an annular external groove 13; this is intended to be positioned in communication with an oil supply passage leading to the engine tappet bore, in an entirely conventional fashion. Said tappet body is provided with a radial passage 14 leading from the groove 13 to an oil receiving chamber within the hollow interior of the body. Said chamber is defined by the cylindrical internal bore 15 of the tappet body in conjunction with the tappet plunger structure, generally designated 16, which is mounted for sliding movement in said bore.

The plunger structure referred to includes a hollow, cylindrical, outer plunger member 17 which is fitted relatively loosely within the bore 15. Member 17 is characterized by an annular,

vertically upstanding wall 18 extending above a circumferential groove 19 which is formed on the exterior of the plunger member. Adjacent the lower end thereof said plunger member is circumferentially relieved at 20 for the reception of a leather packing ring 21 of rectangular section and an O-ring 22 of a suitable, preferably synthetic rubber, packing material. Said O-ring effects an absolute liquid-tight seal between the plunger member 17 and the bore 15 of body 10 at the pressures which are produced in the operation of the tappet. Other than for the close fit of the rings 21, 22 to the plunger and body surfaces, the plunger member 17 is relatively loosely slideable in the bore 15, thereby eliminating the need for close tolerance machining in the manufacture of the member and body.

Said member 17 has axial sliding movement in operation relative to a further, inner plunger member 24 of the structure 16, which is disposed in axially telescoping relation thereto, as shown. Said member 24 includes an upper thrust portion 25 provided with an axially disposed, rounded anvil surface 26 which engages the valve stem 27. It also has an upwardly extending, outer, annular abutment 28 which is disposed beneath, a split retainer ring 29 mounted in a groove in tappet body bore 15. Member 24 is further provided with a stem 30 extending downwardly of its thrust portion 25 and terminating in a cylindrical plunger plug 31, which plug has a relatively close tolerance sliding reception in an axial bore 32 in the lower portion of the outer plunger member 17. However, this fit is not as close as is commonly regarded as essential in existing high pressure type tappets in order to control leak-by, as will be hereinafter referred to.

Said stem plug portion 31 is centrally bored and counterbored from its exposed end to provide an axial passage 33 communicating with a conical valve seat 34. A ball check member 35 is mounted within said counterbore, designated 35' for coaction with said valve seat. A further inclined passage 36 communicates the axial plunger passage 33 with an oil reservoir 37 in the internal plunger member 17 which is defined by the upwardly extending wall 18 of said plunger member.

It should be particularly noted that the overall height of said wall, with reference to the lowermost extremity of its plunger member 17, is slightly less than the overall vertical dimension of the stem 30, with reference to the lower surface of the pressure portion 25 of its plunger member 24. When the tappet is in a "dwell" phase of operation, the vertical clearance space 38 between the wall 18 and plunger member 24 is approximately .012 inch, in a preferred form.

The reservoir 37 maintains a quantity of hydraulic pressure liquid at all times at a substantial level above the passages 33, 36, through which said oil is adapted to flow on the return stroke of the tappet. The oil is supplied to this reservoir past the clearance space 38 through one or more axially extending grooves 39 which are formed on the outer surface of the wall 18 of plunger member 17 and which communicate at their lower ends with the circumferential groove 19 of said member.

A third, lower plunger member 40 completes the plunger structure 16 of the tappet. This member is outwardly flanged at 40' and centrally recessed at 41 for an axial abutting engagement with the lower surface of the inner plunger member 24. It is also provided with a downward ex-

tension 42 about which a coiled compression spring 43 is disposed, said spring acting between the bottom plate 11 of the tappet body and the flange 40' of member 40. An inclined passage 44 in said member leads from the upper surface of the member 40, adjacent the stem counterbore 35' in which the ball check 35 is housed, to the exterior of said lower plunger member. Thus the stem passages 33, 36 are adapted to be communicated with a compression chamber 46 in the tappet 10, defined between the lower portion of the plunger structure 16 and the lower portion of the body. The lower plunger member 40 is merely guided loosely in bore 15.

Assuming that the tappet body 10 is properly fitted in a bore in the engine block, with its pressure plate 11 riding the cam 12 and its anvil surface 26 engaging the valve stem 27, that the external groove 13 is supplied with oil under pressure, that the reservoir 37 has been thus filled with oil through the vertical passages 39 and the clearance space 38, and that this oil has been supplied under pressure to the compression chamber 46 through the passages 36, 33 and 44, then the relationship of the main components of plunger structure 16 and tappet body 10 at the "dwell" phase of tappet operation is approximately as indicated in solid lines in the figure. The extension 42 of the lower plunger member 40 is spaced approximately $\frac{1}{8}$ inch from the body pressure plate 11.

In operation, as the lobe of cam 12 rises, exerting force on the pressure plate 11, the stem 30 of plunger member 24 tends to slide relative to the internal bore 32 of outer plunger member 17, thus exerting pressure against the lower plunger member 40 and spring 43. The resultant slight movement of said member into the compression chamber 46 causes the oil therein to flow upwardly through passage 44, lifting the ball check 35 into sealing relation in the passage 33. Further escape of liquid from compression chamber 46 to the reservoir 37 is prevented.

However, the plunger structure 16 continues to advance, relatively, into the compression chamber 46, increasing the pressure therein, which thus becomes effective on the lower surface of the cylindrical lower portion of plunger member 17. Since this member is absolutely sealed by the O-ring 22, preventing escape of oil around said plunger member, the latter is bodily lifted while the spring-urged member 40 is being held depressed by plunger stem 30. This upward movement of the member 17 is relative to the body 10 and the stem 30. Hence member 17 takes up the clearance 38 between the plunger members 17, 24, causing member 17 to abut member 24. Thereafter the full hydraulic pressure of the compression chamber is effective across the entire transverse area of the plunger member 17, stem 30 and O-ring 22 to elevate the anvil 26 and valve stem 27. Inasmuch as this area is large, the unit pressure is relatively small. In fact, the maximum pressure in compression chamber 46 during operation of the tappet is approximately a third of that involved in the operation of present-day hydraulic tappets. This factor naturally makes possible a much more effective control of leak-by.

As in many hydraulic tappet structures, it is necessary to make provision for the displacement of a slight amount of operating liquid from the compression chamber 46 when the overall length of the plunger structure 16 increases as the result of heat expansion. Such compensa-

tion is accomplished in two ways in the present tappet. Ordinarily, any slow and gradual heat expansion is compensated constantly during the "dwell" phases because the ball check 35 is always open at said "dwell" phase of operation and the liquid volumes adjust themselves automatically. This is true even with an absolute, liquid-tight seal between plunger bore 32 and the relatively slidable stem 30. In the event a sticky valve develops and becomes stuck in an open position, whereas a conventional hydraulic tappet so operates that its plunger would follow and maintain contact with the valve stem, holding the valve in stuck position even after it had freed itself, this possibility is prevented in the present construction by reason of the substantially less close fit of the stem 30 in the bore 32 than in conventional existing tappets. Since the pressure in chamber 46 is low, and since the diameter involved is small, the fit between said bore and stem need not be as close as in the conventional high pressure types. Accordingly, after the stuck valve frees itself and the full force of the spring 43 is effective on plunger member 24, the liquid will escape around stem 30 while ball check 35 is closed until the valve seats itself properly. The normal operating cycle of the tappet then resumes.

The above described tappet can be installed in a standard motor in association with a standard cam shaft, it being only necessary to provide a supply of oil to the tappet from the motor lubrication pressure system. The functioning and timing of the motor are perfectly maintained because the gap or clearance 38 compensates for the backlash which is, at present, "built into" said cam shaft as a standard matter of design. Inasmuch as this clearance is taken up gradually and hydraulically in a chamber which is full of oil, there is no noticeable noise attending the physical contacting of the plunger members 17, 24. Furthermore, in view of the sealing action of the O-ring against bore 15, the latter surface need only be a reamed surface; the outer surface of plunger member 17 may be centerless ground with generous tolerances.

No appreciable difference in tappet performance is occasioned by hot or cold motor operation, or hot or cold oil. The generous clearance between the upper plunger member 24 and the body bore 15 also enables the oil to constantly circulate past these surfaces and carry out of the tappet any vapor or air bubbles that might enter the system.

As stated above, in view of the fact that the pressure in compression chamber 46 is low, the fit of stem portion 31 in the bore 32 need not be as close as in conventional tappet construction, in order to control leak-by. This advantage of efficient leak-by control is further contributed to by the smallness of diameter of said stem portion and bore, for a relatively small total leak-by area is presented.

It will be noted further that the passage 36 in stem 30 is arranged some distance above the bottom of reservoir 37, which insures that any impurities or sludge in the oil which accumulate in the bottom of the reservoir will not clog said discharge or be carried therethrough into compression chamber 46. Moreover, the constant sliding action of the stem portion 30 throughout a distance of approximately .012 inch at every cycle of tappet operation insures that these surfaces be kept clean and open regardless of how dirty or sludgy the oil may become.

Generally, and this applies to the tappet as a whole, the avoidance of close tolerances in the manufacture of the above described tappet contributes substantially to a low cost of production.

I claim:

1. A hydraulic tappet comprising a hollow tubular tappet body, a plunger structure slidable in said body and coacting therewith to define a liquid receiving compression chamber, said structure comprising inner and outer plunger members guided for axial sliding movement in said body and mounted in axially shiftable relation to one another, spring urged means acting between said plunger structure and body to maintain their respective engagement with a valve stem and actuating cam, said plunger members being normally disposed in predetermined axially spaced relation for axial abutting engagement following a predetermined relative axial travel, both of said plunger members being subject to pressure in said compression chamber tending to urge said members in the same axial direction and one thereof being movable in response to said pressure into abutting engagement with the other member after said predetermined relative travel, means providing a liquid-tight seal between said one of said plunger members and said body, and means providing a one-way liquid flow passage between said compression chamber and the side of said plunger structure opposite said chamber, one of said plunger members having a bore paralleling the axis thereof and the other plunger member having a portion slidably received in said bore with relatively small radial clearance to define an annular leak-by passage from said pressure chamber, which leak-by passage is self-cleaning in character due to said relative axial travel and sliding engagement of said last named plunger member portion in said last named plunger member bore.
2. A hydraulic tappet comprising a hollow tubular tappet body, a plunger structure slidable in said body and coacting therewith to define a liquid receiving compression chamber, said structure comprising inner and outer plunger members guided for axial sliding movement in said body and mounted in axially shiftable relation to one another, spring urged means acting between said plunger structure and body to maintain engagement thereof with a valve stem and actuating cam, said plunger members being normally disposed in predetermined axially spaced relation for axial abutting engagement following a predetermined relative axial travel, both of said plunger members being subject to the pressure in said compression chamber tending to urge said members in the same axial direction and the outer member being movable in response to said pressure into abutting engagement with the inner member after said predetermined relative travel, means providing a liquid-tight seal between said outer plunger member and said body, and means providing a one-way liquid flow passage between said compression chamber and the side of said plunger structure opposite said chamber, both members being pressure-shifted after said abutting engagement thereof, one of said plunger members having a bore paralleling the axis thereof and the other plunger member having a portion slidably received in said bore with relatively small radial clearance to define an annular leak-by passage from said pressure chamber, which leak-by passage is self-cleaning in character due to said

relative axial travel and sliding engagement of said last named plunger member portion in said last named plunger member bore.

3. A hydraulic tappet comprising a hollow tubular tappet body, a plunger structure slidable in said body and coacting therewith to define a liquid receiving compression chamber, said structure comprising inner and outer plunger members guided for axial sliding movement in said body and mounted in axially shiftable relation to one another, spring urged means acting between said plunger structure and body to maintain engagement thereof with a valve stem and actuating cam, said plunger members being normally disposed in predetermined axially spaced relation for axial abutting engagement following a predetermined relative axial travel, and both being subject to the pressure in said compression chamber tending to urge said members in the same axial direction and the outer member being movable in response to said pressure into abutting engagement with the other after said predetermined relative travel, means providing a liquid-tight seal between said outer plunger member and said body, and means providing a one-way liquid flow passage between said compression chamber and the side of said plunger structure opposite said chamber, both members being pressure-shifted after said abutting engagement thereof, one of said plunger members having a bore paralleling the axis thereof and the other plunger member having a portion slidably received in said bore with relatively small radial clearance to define an annular leak-by passage from said pressure chamber, which leak-by passage is self-cleaning in character due to said relative axial travel and sliding engagement of said last named plunger member portion in said last named plunger member bore.

4. A hydraulic tappet comprising a hollow tubular tappet body, a plunger structure slidable in said body and coacting therewith to define a liquid containing compression chamber, said structure comprising an outer plunger member guided for axial sliding movement in said body, an inner plunger member guided for axial shifting movement in said outer member and a further member on the compression chamber side of said structure normally disposed in axial abutting engagement with said inner and outer plunger members thereof, a spring normally acting to maintain said abutting engagement, said inner and outer plunger members being normally disposed in predetermined axially spaced relation to one another and both being subject to pressure in said compression chamber tending to move the same in the same axial direction, means providing a liquid-tight seal between said plunger structure and said body, and means providing a one-way liquid flow passage between said compression chamber and the side of said plunger structure opposite said chamber, said outer plunger member having separating movement away from said further member and axially relative to said inner plunger member under increased pressure in said chamber, said inner and outer members being shiftable as a unit under said increased pressure after said lost motion shifting.

5. A hydraulic tappet comprising a hollow tubular tappet body, a plunger structure slidable in said body and coacting therewith to define a liquid containing compression chamber, said structure comprising an outer plunger member guided for axial sliding movement in said body,

an inner plunger member guided for axial shifting movement in said outer member and a further member on the compression chamber side of said structure normally disposed in axial abutting engagement with said inner and outer plunger members thereof, a spring normally acting to maintain said abutting engagement, said inner and outer plunger members being normally disposed in predetermined axially spaced relation to one another for abutting engagement after a predetermined relative axial shifting movement and both being subject to pressure in said compression chamber tending to move the same in the same axial direction, means providing a liquid-tight seal between said plunger structure and said body, and means providing a one-way liquid flow passage between said compression chamber and the side of said plunger structure opposite said chamber, said outer plunger member having separating movement relative to said further member and into abutting engagement with said inner plunger member under increased pressure in said chamber, said inner and outer members being shiftable as a unit under said increased pressure after said lost motion shifting and engagement.

6. A hydraulic tappet comprising a hollow tubular tappet body, a plunger structure mounted relatively loosely in said body for axial sliding movement therein and coacting therewith to define a compression chamber, said structure comprising an outer tubular plunger member guided for axial sliding movement in said body and provided with an abutment element, an inner plunger member mounted in axially shiftable relation to said first plunger and having a portion normally located in predeterminedly spaced relation to said abutment element, and a further member on the compression chamber side of said structure normally disposed in axial abutting engagement with said inner and outer plunger members thereof, a spring urging said plunger structure for engagement with a valve stem and actuating cam, both said plunger members being subject to the pressure of said compression chamber tending to urge the same in the same axial direction and said outer member being movable relative to said inner and further members in response to increase in said pressure, whereby to axially engage said abutment element with said inner plunger portion after traversing said predetermined spacing between said plunger members, means providing a liquid-tight seal between said outer plunger member and said body, and means providing a one-way liquid flow passage between said compression chamber and said reservoir.

7. A hydraulic tappet comprising a hollow tubular tappet body, a plunger structure mounted relatively loosely in said body for axial sliding movement therein and coacting therewith to define a compression chamber, said structure comprising an outer tubular plunger member guided for axial sliding movement in said body and provided with an annular abutment wall affording a liquid reservoir, an inner plunger member mounted in axially shiftable relation to said first plunger and having a portion normally located in predeterminedly spaced relation to said abutment wall, and a further member on the compression chamber side of said structure normally disposed in axial abutting engagement with said inner and outer plunger members thereof, a spring urging said plunger structure for engagement with a valve stem and actuating cam, said

plunger members being subject to the pressure of said compression chamber and said outer member being movable relative to said inner and further members in response to increase in said pressure, whereby to axially engage said annular abutment wall with said inner plunger portion after traversing said predetermined spacing between said plunger members, means providing a liquid-tight seal between said outer plunger member and said body, and means providing a one-way liquid flow passage between said compression chamber and said reservoir.

8. A hydraulic tappet comprising a hollow tubular tappet body, a plunger structure mounted relatively loosely in said body for axial sliding movement therein and coacting therewith to define a compression chamber, said structure comprising an outer tubular plunger member guided for axial sliding movement in said body and provided with an annular abutment wall affording a liquid reservoir, an inner plunger member mounted in axially slidable relation to said first plunger and having a portion normally located in predeterminedly spaced relation to said abutment wall, and a further member on the compression chamber side of said structure normally disposed in axial abutting engagement with said inner and outer plunger members thereof, a spring urging said plunger structure for engagement with a valve stem and actuating cam, said plunger members being subject to the pressure of said compression chamber and said outer member being movable relative to said inner and further members in response to increase in said pressure, whereby to axially engage said annular abutment wall with said inner plunger portion after traversing said predetermined spacing between said plunger members, means providing a liquid-tight seal between said outer plunger member and said body, and means providing a one-way liquid flow passage between said compression chamber and said reservoir, said passage opening to said reservoir substantially above the bottom of the latter.

9. A hydraulic tappet comprising a hollow tubular tappet body, a plunger structure mounted relatively loosely in said body for axial sliding movement therein and coacting therewith to define a compression chamber, said structure comprising an outer tubular plunger member guided for axial sliding movement in said body and provided with an abutment element, an inner plunger member mounted in axially slidable relation to said first plunger and having a portion normally located in predeterminedly spaced relation to said abutment element, and a further member on the compression chamber side of said structure normally disposed in axial abutting engagement with said inner and outer plunger members thereof, a spring urging said plunger structure for engagement with a valve stem and actuating cam, said plunger members being subject to the pressure of said compression chamber and said outer member being movable relative to said inner and further members in response to increase in said pressure, whereby to axially engage said abutment element with said inner plunger portion after traversing said predetermined spacing between said plunger members, means providing a liquid-tight seal between said outer plunger member and said body, and means providing a one-way liquid flow passage between said compression chamber and said reservoir, said inner and outer members having portions

slidably associated with one another with relatively small radial clearance to afford a leak-by passage from said pressure chamber.

10. A hydraulic tappet comprising a hollow tubular tappet body, a plunger structure mounted relatively loosely in said body for axial sliding movement therein and coacting therewith to define a compression chamber, said structure comprising an outer tubular plunger member guided for axial sliding movement in said body and provided with an annular abutment wall affording a liquid reservoir, an inner plunger member mounted in axially slidable relation to said first plunger and having a portion normally located in predeterminedly spaced relation to said abutment wall, and a further member on the compression chamber side of said structure normally disposed in axial abutting engagement with said inner and outer plunger members thereof, a spring urging said plunger structure for engagement with a valve stem and actuating cam, said plunger members being subject to the pressure of said compression chamber and said outer member being movable relative to said inner and further members in response to increase in said pressure, whereby to axially engage said annular abutment wall with said inner plunger portion after traversing said predetermined spacing between said plunger members, means providing a liquid-tight seal between said outer plunger member and said body, and means providing a one-way liquid flow passage between said compression chamber and said reservoir, said inner and outer members having portions slidably associated with one another with relatively small radial clearance to afford a leak-by passage from said pressure chamber.

11. A hydraulic tappet comprising a hollow body and a plunger structure slidably mounted in said body, said plunger structure comprising a pair of plunger members in telescoping relation to one another and adapted for axial abutment with one another in the operation of the tappet, means operatively engaging both of said members in a predetermined relative position thereof, the effective length of one of said plunger members with reference to said engaging means being slightly greater than that of the other to provide an axial space between said members in said predetermined relative position thereof, means subjecting one of said members to hydraulic pressure in the operation of the tappet to shift the same axially the distance of said space relative to the other for said axial abutting engagement, and spring means acting on said engaging means to urge the same and said other member axially in the same direction, said plunger members and engaging means being mounted in said body for axial movement relative to one another.

12. A hydraulic tappet comprising a body and a plunger structure slidable therein, said plunger structure comprising a hollow plunger member of substantial diameter, a further plunger member provided with an axially extending stem portion of relatively small diameter in internal small clearance telescoping engagement with said first named plunger member, said plunger members defining an annular reservoir between said stem portion and the wall of said hollow plunger member and an annular leak-by path externally of said stem portion, and means providing a one-way valve controlled passage through said stem portion.

13. A hydraulic tappet comprising a hollow

external body and a plunger structure slidable therein, said plunger structure comprising a hollow barrel-like plunger member, a further plunger member of generally T-shaped outline in slid- able engagement with the wall of said tappet to seal the latter, said first named plunger member having an axially extending bore in which the stem portion of said further plunger member is slidably received, said plunger members defining an annular reservoir therebetween receiving and 5 confining pressure liquid supplied to the tappet body and an annular leak-by path externally of said stem portion, and means providing a one-way valve controlled passage through said stem portion.

14. A hydraulic tappet comprising a hollow tubular tappet body, a plunger structure slidable in said body on one side of a liquid receiving compression chamber therein, said structure comprising a pair of plunger members mounted in axially shiftable relation to one another, said plunger members being normally disposed in predetermined, axially spaced relation for axial abutting engagement following a predetermined relative axial travel, both of said plunger members being operatively subject to pressure in said compression chamber tending to urge them in the same axial direction and one thereof being movable axially in response to said pressure into abutting engagement with the other after said predetermined relative travel, and means providing a one-way passage through one of said plunger members communicating with said compression chamber, said means including a valve element movable relative to both said members.

15. A hydraulic tappet comprising a hollow tubular tappet body, a plunger structure slidable in said body on one side of a liquid receiving compression chamber therein, said structure comprising a pair of plunger members mounted in axially shiftable relation to one another, spring means acting to maintain engagement of said plunger structure and body with external actuated and actuating members, said plunger members being normally disposed in predetermined, axially spaced relation for axial abutting engagement following a predetermined relative axial travel, both of said plunger members being operatively subject to pressure in said compression chamber tending to urge them in the same axial direction and one thereof being movable axially in response to said pressure into abutting engagement with the other after said predetermined relative travel, and means providing a one-way passage through one of said plunger members communicating with said compression chamber, said means including a valve element movable relative to both said members.

16. A hydraulic tappet comprising a hollow tubular tappet body, a plunger structure slidable in said body on one side of a liquid receiving compression chamber therein, said structure comprising inner and outer plunger members mounted in axially shiftable relation to one another, said plunger members being normally disposed in predetermined, axially spaced relation for axial abutting engagement following a predetermined relative axial travel, both of said plunger members being exposed to pressure in said compression chamber tending to urge them in the same axial direction and one thereof being movable axially in response to said pressure into abutting engagement with the other after said predetermined relative travel, and means providing a one-way passage through one of said

plunger members communicating with said compression chamber, said means including a valve element movable relative to both said members.

17. A hydraulic tappet comprising a hollow tubular tappet body, a plunger structure slidable in said body on one side of a liquid receiving compression chamber therein, said structure comprising inner and outer plunger members mounted in axially shiftable, slidably engaging relation to one another, said plunger members being normally disposed in predetermined, axially spaced relation for axial abutting engagement following a predetermined relative axial travel, both of said plunger members being exposed to pressure in said compression chamber tending to urge them in the same axial direction and one thereof being movable axially in response to said pressure into abutting engagement with the other after said predetermined relative travel, there being a restricted leak-by passage between the slidably engaging surfaces of said plunger members for the controlled escape of liquid under pressure from said compression chamber, and means providing a one-way passage through one of said plunger members communicating with said compression chamber, said means including a valve element movable relative to both said members.

18. A hydraulic tappet comprising a hollow tubular tappet body, a plunger structure slidable in said body and coacting therewith to define a liquid receiving compression chamber, said structure comprising inner and outer plunger members mounted in axially shiftable relation to one another, said plunger members being normally disposed in predetermined, axially spaced relation for axial abutting engagement following a predetermined relative axial travel, a source of pressure liquid, and means providing a one-way liquid flow passage between said compression chamber and said source, said means including a valve element movable relative to both of said plunger members, said members being exposed to pressure in said compression chamber tending to urge them in the same axial direction and one thereof being movable axially in response to said pressure into abutting engagement with the other after said predetermined relative travel.

19. A hydraulic tappet comprising a hollow tubular tappet body, a plunger structure slidable in said body and coacting therewith to define a liquid receiving compression chamber, said structure comprising inner and outer plunger members mounted in axially shiftable, slidably engaging relation to one another, said plunger members being normally disposed in predetermined, axially spaced relation for axial abutting engagement following a predetermined relative axial travel, a source of pressure liquid, and means providing a one-way liquid flow passage between said compression chamber and said source, said means including a valve element movable relative to both of said plunger members, said members being exposed to pressure in said compression chamber tending to urge them in the same axial direction and one thereof being movable axially in response to said pressure into abutting engagement with the other after said predetermined relative travel, there being a restricted leak-by passage between the slidably engaging surfaces of said plunger members for the controlled escape of liquid under pressure from said compression chamber to said source.

20. A hydraulic tappet comprising a hollow tubular tappet body, a plunger structure slidable

in said body on one side of a liquid receiving compression chamber therein, said structure comprising inner and outer plunger members mounted in axially shiftable, slidably engaging relation to one another, spring means acting to maintain engagement of said plunger structure with external actuated and actuating members, said plunger members being normally disposed in predetermined, axially spaced relation for axial abutting engagement following a predetermined relative axial travel, a source of pressure liquid, and means providing a one-way liquid flow passage between said compression chamber and said source, said means including a valve element movable relative to both of said plunger members, said members being exposed to pressure in said compression chamber tending to urge them in the same axial direction and one thereof being movable axially in response to said pressure into abutting engagement with the other after said predetermined relative travel, there being a re-

stricted leak-by passage between said plunger members for the controlled escape of liquid under pressure from said compression chamber.
